UNITED STATES PATENT OFFICE.

EDWARD POSSON, OF CHICAGO, ILLINOIS.

SELF-CENTERING SIDE BEARING.

Application filed September 18, 1919. Serial No. 324,571.

To all whom it may concern:

Be it known that I, EDWARD POSSON, a citizen of the United States, residing at Chicago, in the county of Cook and State of Illinois, have invented certain new and useful Improvements in Self-Centering Side Bearings, of which the following is a specification.

This invention relates to side bearings for railway cars, and its purpose is to provide an improved device adapted for attachment to a car truck to form an anti-friction bearing for a part carried by the body of the car.

The principal object of the invention is to provide an improved roller side bearing having improved means for mounting the roller. Another important object is to provide an improved self-centering side bearing. A further object is to provide a side bearing provided with a roller having ball-bearing trunnions. Still another object is to provide a casing and a cylindrical roller provided with registering depressions adapted to receive spherical trunnion members which permit relative longitudinal movement of the roller and the casing. Other objects relate to various features of construction and arrangement which will be pointed out more fully hereinafter.

The nature of the invention will be understood from the following specification taken with the accompanying drawings, in which one embodiment is illustrated.

In the drawings—

Figure 1 is a top plan view of the invention showing a portion thereof in horizontal section on the line 1—1 of Fig. 2;

Fig. 2 is an end elevation of the invention showing a portion thereof in vertical section on the line 2—2 of Fig. 1;

Fig. 3 shows a side elevation of the invention; and

Fig. 4 is a longitudinal sectional view on the line 4—4 of Fig. 1, with the cylindrical roller removed, showing the inner side of the side wall in elevation.

The invention comprises a casing 10 having a lower wall or base plate 11 provided with a plurality of apertures 12 adapted to be engaged by bolts for securing the casing to the bolster or other part of the car. Parallel side walls 13 are formed integrally with and extend upwardly from the base plate 11, and these walls are reinforced against outward bending by the integrally

formed ribs 14 located at the ends thereof. Other ribs or lugs 15 extend upwardly from the base plate 11 transversely of the casing between the side walls 13, and these lugs are adapted to form stops for a steel wear plate 16 which is adapted to rest on the base plate 11. This wear plate engages longitudinal grooves or guideways 17 which are formed in the side walls 13 and extend inwardly from one end of the casing, as shown particularly in Fig. 4. After being inserted in position against the lugs 15, the wear plate is held in position by a transverse key 18 which engages apertures 19 in the side walls. The ends of the key 18 are transversely bent after insertion, as shown at 18^a, to prevent removal of the key.

The steel wear plate 16 is adapted to support a substantially spherical roller 20 which is provided with bevelled end surfaces, as shown at 20^a, and which is further provided at each end with a centrally located circular recess 21 of the form illustrated particularly in Figs. 1 and 2. These recesses 21 are adapted to register with other recesses 22 which are formed in the side walls 13, the side walls being provided with outwardly projecting parts 23 to receive these recesses. The outer ends of the projecting parts 23 are provided with circular apertures 25 which extend through the hub portions 26. Reinforcing ribs 27 extend downwardly from the hubs 26 to the base plate 11. The apertures 25 are normally closed by cylindrical plugs or caps 29 which are secured in position by vertically extending rivets or pins 30 which pass through the cap members and through the annular walls of the hubs 26. Upon removal of the cap members 29, the apertures 25 are adapted to permit the insertion of spherical ball-bearings 31 into the chambers which are formed by the registering recesses 21 and 22. While the recesses 21 are circular in form, it will be observed that the recesses 22 are elongated longitudinally of the casing parallel to the path of travel of the roller 20, and the outer walls of the recesses 21 and 22 are curved, as shown at 21^a and 22^a, respectively, to conform to the spherical contour of the balls 31. The vertical dimension of each recess 22 is less than that of the registering recesses 21 but larger than the diameter of the coating ball 31, and in normal operation the balls are adapted to rest on the lower curved surfaces 21^a and 22^a of the

registering recesses, as shown in Fig. 2. The upper walls 22^b of the recesses 22 are horizontal, and the lower walls 22^c are formed in two parts which converge downwardly 5 toward the center of the recess, as illustrated in Figs. 3 and 4, so that the balls 31 have a normal tendency to travel down the inclined walls 22^c to the central position illustrated in Fig. 4. The opposite walls of the 10 registering depressions are preferably spaced apart distances which are slightly greater than the diameters of the balls 31.

When the side bearing, as above constructed, is secured to the bolster or other 15 part of the car truck, for example, the rollers 20 are adapted to coast with wear plates carried by the underside of the car body and upon relative movement of the truck with respect to the body, each roller 20 20 travels upon its supporting wear plate 16. During this movement, the spherical balls 31 serve to guide the roller 20, and at the same time the balls travel in the chambers formed by the registering recesses 21 and 22 25 in order to permit relative movement of the roller with respect to the casing, thus permitting a free movement of the roller and reducing the friction on the side walls of the casing. The balls 31 thus form movable 30 trunnions for the rollers 20, being adapted to permit free endwise movement of the roller and to return the roller automatically to its central position after its release by the engagement therewith of the wear plate 35 carried by the body of the car. When the roller 20 moves toward one end of the casing, the balls 31 travel up the inclined walls 22^c, this movement being permitted by the fact that the recesses 21 are larger in 40 diameter than the balls 31, and this movement of the balls continues until they reach the ends of the recesses 22. When the roller 20 is released, the balls 31 automatically travel by the gravity to their central positions, and 45 thus return the roller 20 to its central position. The side bearing is thus automatically self-centering and the mounting of the roller permits some angular movement thereof to correspond to the relative angular 50 movement of the truck with respect to the car body.

Although I have shown and described a single embodiment of the invention for purposes of illustration, it will be understood 55 that it may be constructed in various other forms without departing from the scope of the appended claims.

What I claim is:

1. In combination, a casing, a roller 60 adapted to travel horizontally within said

casing, said roller having apertures in the ends thereof, said casing having apertures adapted to register with said first-named apertures, and balls inserted in said apertures, said balls being adapted to travel therein divergently from the direction of travel of said roller and to return said roller to normal position within said casing. 65

2. In combination, a casing, a roller mounted on said casing and having depressions in its ends, said casing having other depressions adapted to register with the depressions in said roller, balls inserted in said registering depressions, and removable plugs in said casing to permit the insertion 70 of said balls. 75

3. In combination, a casing having upwardly extending side walls, a roller adapted to travel between said walls, said roller having depressions in the ends thereof, said side walls having other depressions adapted to register with the depressions in said roller, balls engaging said registering depressions, said side walls having apertures therethrough to receive said balls, and cap 80 members normally closing said apertures. 85

4. In combination, a casing having upwardly extending side walls, a cylindrical roller adapted to travel between said side walls, a removable wear plate mounted between said side walls to support said roller, said roller having depressions in the ends thereof, said side walls having depressions to register with the depressions in said roller, and balls engaging said registering 90 depressions, said depressions in said roller being circular, said depressions in said side walls being elongated longitudinally of said casing. 95

5. In combination, a casing having upwardly extending side walls, a cylindrical roller adapted to travel between said side walls, a removable wear plate mounted between said side walls to support said roller, said roller having depressions in the ends thereof, said side walls having depressions to register with the depressions in said roller, and balls engaging said registering 100 depressions, said depressions in said roller being circular, said depressions in said side walls being elongated longitudinally of said casing, said depressions in said side walls having lower surfaces which converge 105 downwardly to effect the automatic return of said balls to their central positions by 110 gravity after said roller has been moved in either direction longitudinally. 115

In testimony whereof, I have subscribed my name.

EDWARD POSSON.
